UNITED STATES PATENT OFFICE

122,742

DESIGN FOR A DRESS ENSEMBLE

Moe Glatman, New York, N. Y.

Application August 16, 1940, Serial No. 94,467

Term of patent 3½ years

To all whom it may concern:

Be it known that I, Moe Glatman, a citizen of the United States of America, residing in New York city, county of New York, and State of New York, have invented a new, original, and ornamental Design for a Dress Ensemble, of which the following is a specification, reference being had to the accompanying drawing, forming part thereof, wherein:

I claim:

The ornamental design for a dress ensemble, substantially as shown.

MOE GLATMAN.
